(No Model.)

A. L. PITNEY.

ROPE OR LINE CLASP.

No. 357,856.

Patented Feb. 15, 1887.

ATTEST -

John S. Scott.
Harry L. Amer.

INVENTOR -

Albert L. Pitney.

UNITED STATES PATENT OFFICE.

ALBERT L. PITNEY, OF WASHINGTON, DISTRICT OF COLUMBIA.

ROPE OR LINE CLASP.

SPECIFICATION forming part of Letters Patent No. 357,856, dated February 15, 1887.

Application filed November 8, 1886. Serial No. 218,358. (No model.)

To all whom it may concern:

Be it known that I, ALBERT L. PITNEY, of Washington, in the District of Columbia, have invented a certain Improvement in Rope or Line Clasps, of which the following is a full, clear, and exact description, reference being had to the accompanying drawings, making part of this specification, in which like letters refer to like parts in the device.

Figure 1 is a longitudinal sectional view of my improved cord-fastener with the cord in position as in actual use. Fig. 2 is a vertical cross-section of Fig. 1 at x x . Figs. 3, 4, and 5 are perspective views of the lever, showing the opening for the cord in the long arm. Fig. 6 is a perspective face view of the fastener when combined with a label-holder. Fig. 7 is a vertical cross-section of Fig. 6 at x x . Fig. 8 is a perspective view of the clasp, with an opening in the side of case for convenience in relieving tension when the device is used as an awning or sail holder.

My present invention has for its object a simple and reliable automatic device for fastening cords, &c., and to obviate the necessity of tying and untying and the labor incident thereto.

I am aware that heretofore cord-fasteners have been constructed with levers pivoted away from their ends, and have found in actual practice that this manner of construction is faulty, the cord being compelled to deflect too much from a direct line to run smoothly. This fault is disastrous to a perfect fastener, and is most apparent when attempting to release the cord.

The object of my present invention is to overcome and remove the objectionable features and to lessen the cost of manufacture.

My invention consists in a case through which the line is passed and a clamping device that is by the strain upon the rope made to press the same tightly against the bottom of the case.

This improved clasp may be constructed in various forms and its parts in a variety of ways without involving any difference in principle. Some of the different forms which have suggested themselves have, however, their own special advantages, and in Fig. 1 I have shown the construction preferred.

In order that others skilled in the art or manufacture may fully understand my invention, I will particularly describe the construction preferred, and regard the same as typical of all, reference being had to the accompanying drawings.

A represents a long, narrow, open case or retainer, of metal or any other suitable material, that, with the lever placed in proper position, forms a complete line-clasp. The case at the front end, a , is drawn down and closed on top so there is just room enough to allow of the passage of the cord. This is for the purpose of keeping the end of the cord below the free end of the lever, that there may always be a bearing upon the lever and a pressure upon the cord where it passes under the toothed or projecting under face of the lever.

B represents a lever with an opening, d , at the end to allow the passage of the cord, in order to form a bearing thereon when the strain or draw is toward the front end of the clasp.

C is a shoulder to form a stop to prevent raising the lever too high.

The lever may be used in the same clasp singly or in duplicate, &c., as desired, there being one lever for each cord.

D represents an ordinary label-holder, that is attached to and acts as a bottom to the case A when it is desired to combine the cord-fastener with a label-holder.

To open the clasp or release the cord, take hold of the exposed end of the lever, raise, and draw toward you.

Having fully described my invention, what I claim, and desire to secure by Letters Patent, is—

1. In a cord-fastener, the combination of the case with the lever pivoted at its rear end to the upper sides of the case, and also having an opening through the other end to retain the cord, and provided with a toothed or raised surface on the lower part for clamping the cord to the case, substantially as shown and described.

2. In a cord-fastener, the combination of the case with the lever pivoted at its rear end to the upper sides of the case, and also having an opening through the other end to retain the cord, and provided with a toothed or

raised surface on the lower part for clamping the cord, and with a shoulder on the upper rear part to prevent raising the lever too high when relieving the tension of the cord, substantially as shown and described.

3. In a cord-fastener, the combination, with the case provided with a guide at its front end, of the lever pivoted at its rear end to the upper sides of the case, the other end being

provided with an elbow or arm for retaining the cord, and a shoulder on the upper rear part to prevent raising the lever too high when relieving the tension of the cord, substantially as shown and described.

ALBERT L. PITNEY.
